APPARATUS FOR DEFIBERIZING BAGASSE

Leo Freeman, Baton Rouge, La., assignor to Gruendler Crusher and Pulverizer Company, St. Louis, Mo., a corporation of Missouri

Application February 25, 1953, Serial No. 338,731

7 Claims. (Cl. 19—90)

This invention relates in general to certain new and useful improvements in apparatus for defiberizing bagasse.

It is the primary object of the present invention to provide means for separating a pith-containing fibrous material, such as bagasse, into pith and fiber in a simple, efficient, and continuous manner without cutting up the fibers or materially reducing their lengths.

It is another object of the present invention to provide means for separating the fibers from the pith in bagasse or similar fibrous mass which comprises the step of subjecting the bagasse to a water spray whereby the pith is removed efficiently and the fibers are carried along by the spray for ultimate collection.

It is an additional object of the present invention to provide a defiberizing machine of the type stated integrally containing a separator chamber longitudinally disposed above a pith-receiving compartment and a fiber-receiving compartment.

It is a further object of the present invention to provide a defiberizing machine of the type stated including a longitudinal chamber and means associated therewith for adjustably constricting the size of such chamber from one end to the other to compensate for reduction in volume of the material being processed as it passes through the longitudinal chamber.

With the above and other objects in view, my invention resides in the novel features of form, construction, arrangement, and combination of parts presently described and pointed out in the claims.

In the accompanying drawings (two sheets)—

Figure 1 is a vertical sectional view of a defiberizing machine constructed in accordance with and embodying the present invention; and

Figures 2 and 3 are transverse sectional views taken along lines 2—2 and 3—3, respectively, of Figure 1.

Referring now in more detail and by reference characters to the drawings, which illustrate a preferred embodiment of the present invention, A designates a defiberizing machine comprising a rectangular casing or housing shell 1 having side walls 2, 2', and end walls 3, 3'. Suitably secured, as by welding, to the outwardly presented faces of the end walls 3, 3', adjacent their lower margins are angle sections 4, 4', respectively, the lateral flanges of which are each provided with a plurality of spaced apertures 5, 5', respectively, for receiving lag screws 5 whereby the machine A may be maintained rigidly upon beams or other supporting surface. Provided within the casing 1 is a partition plate 6 extending transversely thereacross in parallel relation to the end walls 3, 3', being spaced a relatively short distance from the end wall 3, whereby the casing 1 is divided into large and small compartments 7, 8.

Centrally provided in the upper margins of the end walls 3, 3', and the partition plate 6 are aligned recesses 9, 9', 10, respectively, through which longitudinally extends a shaft 11, the ends of which project outwardly beyond the end walls 3, 3', and are supported by bearings 12, 12'. Said bearings 12, 12', are conventionally bolted

2

upon horizontal cross plates 13, 13', respectively, which are, in turn, supported by brackets 14 welded, or otherwise suitably secured, to the casing 1. Adjacent each of its extreme end portions, the shaft 11 is provided with key-ways 15 for operable engagement with a conventional type prime mover (not shown).

Along that portion of its length which extends through the compartment 7, the shaft 11 is provided with a diametrically enlarged section 16 externally threaded at its opposite ends and keyed upon the shaft section 16 for rotation therewith is a plurality of rotor disks 17 separated by spacer rings 18. Adjacent their outer margins, the rotor disks 17 are provided with four equally spaced apertures 19 aligned for receiving longitudinally extending rods 20 which are secured at their ends against the outer face of the end disks 17 by cotter pins 21. Swingably mounted on the rods 20 intermediate successive pairs of the rotor disks 17 is a plurality of hammer members 22. The first three sets of hammers 22 from the left end of the machine A (reference being made to Figure 1) are straight-ended and the remaining sets of hammers 22 are twisted at their outer ends.

Disposed about the lower portion of the hammers 22 is a semi-cylindrical foraminous screen 23 which is spaced upwardly from the lower margins of the end walls 3, 3', and the partition plate 6. At its upper margins, the screen 23 is secured to longitudinally extending angle members 24, 24' which are secured at their ends to the end wall 3 and the partition plate 6.

30 Mounted upon the shaft 11 within the compartment 8 is an agitator 25 comprising a half-collar member 26 having a pair of diametrically opposed outwardly extending arms 27 and a companion member 28 provided with relatively short laterally extending flanges 29 suitably apertured for receiving bolts 30 for securing to the half-collar member 26 about the shaft 11, with the flanges 29 adjacent the inner portions of the arms 27 (Figure 3).

35 Welded or otherwise suitably secured along the upper margins of the side walls 2, 2', and end walls 3, 3' are outwardly projecting flange members 31, each having a plurality of spaced apertures 32 for receiving bolts 33 which extend through registering apertures 34 in a corresponding lateral flange 35 integrally formed on a cover or housing 36 having integral end walls 37, 37', and 40 upwardly and inwardly extending side portions 38, 38'. The side portion 38' is curved inwardly, as at 39, and thence outwardly to provide a humped portion or longitudinal top-chamber 40, which is disposed above the outer limits of the peripheral arc of the hammers 22 and 45 interiorly provides a tube-like separator chamber 41 in elevated relation to, and communicating with, the compartments 7, 8. The end walls 37, 37', are provided centrally in their lower margins with recesses 42, 42', for co-operation with the recesses 9, 9', in the end walls 3, 3', respectively, in forming openings for the shaft 11. Adjacent and outwardly of each of said openings, there is disposed upon the shaft 11 an annular seal or packing ring 43 maintained in position by retainer members 44 suitably secured to the casing 1 and the cover or housing 36 by bolts 45.

60 Provided in the upper portion of the end wall 37 of the cover or housing 36 is an enlarged aperture 46 provided with an outwardly extending pipe-like fitting 47 integrally formed in said cover or housing 36, said fitting 47 being 65 provided on its outer end with a peripheral flange 48 for suitable connection to a conventional type of pressure-feed device (not shown). Also provided in the end wall 37 adjacent to the upper portion of the aperture 46 is a hinge member 49 for rockably supporting a somewhat hemi-cylindrical throttling plate 50 which conforms in 70 transverse cross-sectional shape to the cross-sectional contour of the longitudinal top-chamber 40 and is pro-

vided at its rear end with a ball-socket fitting 51 for self-seated engagement with the ball-end 52 of a depending adjustment screw 53 threadedly mounted in and projecting upwardly through the longitudinal top-chamber 40. As will be seen by reference to Figure 1, the throttling plate 50 is approximately of the same length as the top-chamber 40 and is similarly cut back or relieved along its forward surface margins, as at 54, for clearance with respect to the end wall 37. The adjustment screw 53 is conventionally provided at its upper end with a suitable handle 55 and the top-chamber 40 of the housing 36 is conventionally provided with a ring 56 for receiving a winch cable hook or other similar lifting element to facilitate removal when it is necessary to clean, adjust, or repair the defiberizing machine A.

In operation, bagasse or the pulpy fibrous mass is pumped under pressure through the fitting 47 into the separator chamber 41 in large volume so as, in effect, to choke feed the machine A. The incoming bagasse will, through its feed pressure and the driving pressure of the water, be carried through the separator chamber 41. As the bagasse or pulpy mass moves along, the pith readily absorbs substantial quantities of water, thereby rapidly increasing its density so that this added weight will cause it to drop downwardly into the chamber 7, wherein it is subjected to a beating action by the hammers 22 and then descends through the screen 23 into any suitable collecting sump (not shown). With the removal of the pith, as so described, the fibrous portion of the bagasse is moved along above the hammers 22 and thus prevented from being damaged thereby. The fibrous material will, upon reaching the opposite end of the separator chamber 41, drop downwardly through the compartment 8 for ultimate collection in any suitable container. The agitator 25 serves merely to assist the downward descent of the fibrous material and prevent any undue clogging or damming within the compartment 8. As the stream of bagasse moves along and through the longitudinal top-chamber 40 formed above the hammers 22 by the housing 36, it is necessary that a substantially uniform back pressure be maintained upon the material and that the loss of volume due to pith removal be compensated. This is accomplished by threading the screw 53 up or down as may be required to adjust the angularity of the throttling plate 50 which progressively constricts the longitudinal top-chamber 40 to offset the reduction in volume resulting from pith removal and insure that a substantially uniform pressure is maintained on the material at all times. As the bagasse stream traverses the length of the top-chamber 40, it will be completely depithed and the fibers discharged downwardly through the compartment 8 will be undamaged so far as length or structure is concerned and will be totally free of pith.

It should be understood that changes and modifications in the form, construction, arrangement, and combination of the several parts of the apparatus and in the several steps of the method may be made and substituted for those herein shown and described without departing from the nature and principle of my invention.

Having thus described my invention, what I claim and desire to secure by Letters Patent is:

1. A defiberizing machine comprising a compartmented casing, having compartments arranged in side-by-side relation, a cover member disposed closurewise upon said casing, said cover member being enlarged to form a tubular chamber over and above said compartments and being provided over one compartment with a bagasse-receiving aperture, another of said compartments having an outlet aperture and an elongated arcuate plate hingedly mounted in the tubular chamber adjacent the bagasse-receiving aperture and extending lengthwise along the top of the tubular chamber toward the outlet aperture, rotary hammers operatively mounted in one of said compartments in such a manner that the outermost peripheral portions of

the hammers will describe a hammer circle which is spaced from the arcuate plate, and means for adjusting the position of said plate angularly with respect to the longitudinal axis of said chamber for choking down the space above the hammer circle and thereby controlling the flow of material from the bagasse-receiving aperture to the outlet aperture.

2. A defiberizing machine comprising a compartmented casing having compartments arranged in side-by-side relation, rotary hammers disposed in said casing, a cover member of approximately hemi-cylindrical shape disposed closurewise upon said casing over and above the hammers in the provision of an elongated tubular chamber and being provided over one compartment with a bagasse-receiving aperture, another of said compartments having an outlet aperture and an elongated arcuate plate hingedly mounted in the tubular chamber adjacent the bagasse-receiving aperture and extending lengthwise along the top of the tubular chamber toward the outlet aperture, and means for adjusting the position of said plate angularly with respect to the longitudinal axis of said chamber for choking down the space above the hammer circle and thereby controlling the flow of material from the bagasse-receiving aperture to the outlet aperture.

3. A defiberizing machine comprising a compartmented casing having compartments arranged in side-by-side relation, a cover member disposed closurewise upon said casing, said cover member being shaped to form an elongated tubular chamber over and above said compartments and being provided over one compartment with a bagasse-receiving aperture, another of said compartments having an outlet aperture, a substantially hemi-cylindrical plate having its longitudinal axis extending generally lengthwise of the tubular chamber, said plate being hingedly mounted in the tubular chamber adjacent the bagasse-receiving aperture and extending lengthwise along the top of the tubular chamber toward the outlet aperture, rotary hammers operatively mounted in one of said compartments in such a manner that the outermost peripheral portions of the hammers will describe a hammer circle which is spaced from the arcuate plate, and means for adjusting the position of said plate angularly with respect to the longitudinal axis of said chamber for choking down the space above the hammer circle and thereby controlling the flow of material from the bagasse-receiving aperture to the outlet aperture.

4. A defiberizing machine comprising a casing having first and second compartments arranged in side-by-side relation, a shaft extending through said casing, a beater means mounted upon said shaft within said first compartment, an agitating member mounted on said shaft within said second compartment, a cover member disposed closurewise upon said casing, said cover member being shaped to form an elongated tubular chamber over and above said compartments, said cover member being provided at one end with a material-receiving inlet aperture opening into said chamber, said tubular chamber communicating with said first and second compartments, said second compartment having an outlet, a substantially hemi-cylindrical plate having its longitudinal axis extending generally lengthwise of the tubular chamber, said plate being hingedly mounted in the tubular chamber adjacent the inlet aperture and extending lengthwise along the top of the tubular chamber toward the outlet aperture, and means for adjusting the position of said plate angularly with respect to the longitudinal axis of said chamber for choking down the space above the beater means and thereby controlling the flow of material from the inlet aperture to the outlet aperture.

5. A defiberizing machine comprising a hammer cage having spaced parallel end walls and a rotary shaft extending lengthwise through the hammer cage between said end walls, said cage being subdivided longitudinally of the shaft into first and second compartments, said second

compartment having an outlet, hammers operatively mounted on that portion of the shaft which is located in the first compartment, a cover member disposed closurewise upon said cage, a feed-pipe opening into the cover member through one of said end walls and above the first compartment and above the hammer circle, said cover member being spaced upwardly from the upper portion of the hammer circle in the provision of a tubular chamber extending in parallel relation to the shaft and in elevated relation to said first and second compartments, and a plate hingedly mounted on the cover adjacent the feed-pipe and extending lengthwise along the top of said tubular chamber, said plate being adjustable toward the hammer circle for adjustably choking down the space thereover.

6. A defiberizing machine comprising a hammer cage having spaced parallel end walls and a rotary shaft extending lengthwise through the hammer cage between said end walls, said cage being subdivided longitudinally of the shaft into first and second compartments, said second compartment having an outlet, hammers operatively mounted on that portion of the shaft which is located in the first compartment, a cover member disposed closurewise upon said cage, a feed-pipe opening into the cover member through one of said end walls and above the first compartment and above the hammer circle, said cover member being spaced upwardly from the upper portion of the hammer circle in the provision of a tubular chamber extending in parallel relation to the shaft and in elevated relation to said first and second compartments, a transversely curved plate hingedly mounted on the cover adjacent to the feed-pipe and extending lengthwise along the top of the tubular chamber, and means operatively associated with the plate for swinging the plate angularly downwardly toward the hammer circle, whereby to choke down the space over the hammer circle in gradually increasing degree from the feed-pipe to the second compartment.

hammer circle, whereby to choke down the space over the hammer circle in gradually increasing degree from the feed-pipe to the second compartment.

7. A defiberizing machine comprising a hammer cage having spaced parallel end walls and a rotary shaft extending lengthwise through the hammer cage between said end walls, said cage being subdivided longitudinally of the shaft into first and second compartments, said second compartment having an outlet, hammers operatively mounted on that portion of the shaft which is located in the first compartment, a cover member disposed closurewise upon said cage, a feed-pipe opening into the cover member through one of said end walls and above the first compartment and above the hammer circle, said cover member being spaced upwardly from the upper portion of the hammer circle in the provision of a tubular chamber extending in parallel relation to the shaft and in elevated relation to said first and second compartments, a transversely curved plate hingedly mounted on the cover adjacent to the feed-pipe and extending lengthwise along the top of the tubular chamber, and means operatively associated with the plate for swinging the plate angularly downwardly toward the hammer circle, whereby to choke down the space over the hammer circle in gradually increasing degree from the feed-pipe to the second compartment.
